UNITED STATES PATENT OFFICE.

MARTIN HEMLEB, OF ELIZABETH, NEW JERSEY, ASSIGNOR TO THE SINGER MANUFACTURING COMPANY; A CORPORATION OF NEW JERSEY.

ROTARY-HOOK SEWING-MACHINE.

1,226,973.

Specification of Letters Patent.

Patented May 22, 1917.

Application filed August 21, 1914. Serial No. 857,811.

To all whom it may concern:

Be it known that I, MARTIN HEMLEB, a citizen of the United States, residing at Elizabeth, in the county of Union and State 5 of New Jersey, have invented certain new and useful Improvements in Rotary-Hook Sewing-Machines, of which the following is a specification, reference being had therein to the accompanying drawings.

10 This invention has for its primary object to provide simple and effective means for replacement of the bobbins in circularly moving loop-takers having journaled therein thread-cases restrained from circular 15 movement therewith, and applicable to loop-takers comprising rotary loop-seizing members having continuous or reciprocatory movements upon axes passing through their body portions.

20 According to the present improvement, the cup-shaped body of the loop-taker has journaled therein a thread-case provided with a central thread-cavity and has formed in its rim a radial slot crossed by a fulcrum- 25 pin upon which is mounted an angular bobbin-ejecting lever having a radial arm extending beneath and adapted to enter the thread-cavity of the thread-case and a second upwardly extending arm disposed exterior to the loop-taker rim and provided 30 with a finger-piece presented for convenient pressure by the operator for ejecting a bobbin from the thread-case.

The main-shaft journaled in the over- 35 hanging member of the bracket-arm is connected by intermeshing speed-accelerating bevel gears to an upright shaft journaled within the hollow bracket-arm standard and provided with angularly disposed cranks 40 connected by pitmen to similar cranks upon the vertical hook-shaft upon which the loop-seizing member is secured for co-operation with the usual reciprocating needle.

In the drawings, Figure 1 is a side elevation of a sewing machine embodying the 45 present improvements with the frame partly in section, and Fig. 2 is a bottom plan view of the same. Fig. 3 is a plan, upon an enlarged scale, of a portion of the bed-plate, 50 the throat-plate, and the loop-taker, and Fig. 4 a sectional elevation of the same. Fig. 5 is a perspective view of the bobbin-ejector detached.

The frame of the machine comprises the 55 usual bed-plate 1 from which rises the hol-

low bracket-arm standard 2 having the tubular lateral member 3 within which is journaled the main or driving shaft 4 having the usual operative connection with the reciprocating needle-bar 5 carrying the needle 6.

Depending from the bed-plate 1 is the bearing bracket 7 in which is journaled the vertical loop-taker shaft 8 having secured thereon by means of the set-screw 9 the hub 60 10 of the cup-shaped loop-seizing member 11 provided with the beak 12. The member 11 has journaled therein in a manner well known, by means of a tongue-and-groove connection, the thread-case 13 formed with 65 the thread-cavity 14 containing the lower-thread bobbin 15 and provided with the lateral finger 16 embraced by the spaced holding lugs 17 depending from the throat-plate 18 for restraining the thread-case from rotation. The thread-case has in its bottom a central opening 19 for access to the bobbin.

As represented in Figs. 3 and 4, the loop-seizing member 11 has a radial slot 20 extending from one side of its axis into and 70 through the rim upon the opposite side thereof, and sustains within the rim the cross fulcrum-pin 21 threaded at one end and tapped into said rim. The bobbin-ejecting angle-lever comprises a lateral arm 75 22 disposed within the slot 20 beneath the thread-case and an upwardly extending arm 23 terminating in the finger-piece or plate 24 disposed externally to the member 11 apertured ears 22' being turned up from the base 80 of the arm 22 and entered by the fulcrum-pin 21. Between the ears 22', the fulcrum-pin is surrounded by a coil-spring 25 having one extremity 26 engaging the bobbin-ejector arm 23 and the other extremity 27 in 85 engagement with the member 11, by means of which the ejecting lever is yieldingly maintained in retracted position with the arm 22 in the lower position, as represented in Fig. 4.

The loop-seizing member 11 being turned to expose the finger-piece 24 at one side of the throat-plate, pressure upon such finger by the operator serves to lift the bobbin sufficiently above the wall of the thread-case 105 to enable its upper flange to be grasped by the operator for removal.

The lower end of the loop-taker shaft 8 has secured thereon by means of the set-screw 28 the hub 29 of a crank member 110

provided with the crank-studs 30 and 31 disposed in offset relation relatively to the shaft 8, and a similar crank element 32 is fixed upon the lower end of the vertical intermediate shaft 33 which is journaled within the bearing bosses 34 and embraced by the standard 2. The crank-studs of the shafts 8 and 33 are connected by means of the pitmen 35 to establish driving relation between said shafts. The shaft 33 has fixed upon its upper end the bevel pinion 36 meshing with the bevel gear 37 of double its size fixed upon the main-shaft 4 by which the intermediate shaft is driven at twice the speed of the main-shaft, its movements being imparted to the loop-taker shaft through the described crank-and-pitman connection.

Having thus set forth the nature of the invention, what I claim herein is:—

20 1. A sewing machine loop-taker comprising a rotary loop-seizing member, a thread-case formed with a thread-cavity and journaled in said member in which it is restrained from rotary movement, and a bobbin-ejector sustained by said loop-seizing member independently of the thread-case and adapted to enter said thread-cavity.

25 2. A sewing machine loop-taker comprising a cup-shaped loop-seizing member, a thread-case formed with a thread-cavity and journaled in said member in which it is restrained from rotary movement, and a bobbin-ejector comprising an angle-lever journaled in the rim of the loop-seizing member and having a radially extending arm adapted to enter said thread-cavity.

3. A sewing machine loop-taker comprising a cup-shaped loop-seizing member formed at one side with a radial slot passing through its wall, a thread-case formed with a thread-cavity and journaled in said member in which it is restrained from rotary movement, a fulcrum-pin extending across said slot of the loop-seizing member, a bobbin-ejector comprising an angle-lever formed at the edges with spaced parallel ears entered by said fulcrum-pin and having one arm extended radially and adapted to enter the thread-cavity and another arm disposed mainly exterior to the loop-seizing member and provided with a finger-piece, and a spring surrounding said fulcrum-pin intermediate said ears of the bobbin-ejecting angle-lever and connected at opposite ends respectively with the latter and the loop-seizing member.

4. A sewing machine loop-taker mechanism comprising a driving shaft, a rotary loop-seizing member mounted on said shaft, a thread-case formed with a thread-cavity and journaled in said member in which it is restrained from rotary movement, and a bobbin ejector sustained by said loop-seizing member independently of the thread-case and adapted to enter said thread-cavity.

In testimony whereof, I have signed my name to this specification, in the presence of two subscribing witnesses.

MARTIN HEMLEB.
